UNITED STATES PATENT OFFICE.

FREDERICK B. KOONTZ, OF TULSA, OKLAHOMA, ASSIGNOR TO COSDEN & COMPANY, OF TULSA, OKLAHOMA, A CORPORATION OF OKLAHOMA.

PROCESS OF AND APPARATUS FOR CRACKING HYDROCARBONS.

Application filed May 8, 1924. Serial No. 711,866.

To all whom it may concern:

Be it known that I, FREDERICK B. KOONTZ, a citizen of the United States, residing at Tulsa, in the county of Tulsa and State of Oklahoma, have invented certain new and useful Processes of and Apparatus for Cracking Hydrocarbons, of which the following is a specification.

This invention relates to improvements in processes of and apparatus for cracking hydrocarbons, such as high boiling point petroleum hydrocarbons, to obtain relatively low boiling point products.

One of the objects is to produce a cracking system wherein the cracking operation can be carried out continuously for a relatively long period, and this object is accomplished partly by the elimination of carbon from the passageways in which it would otherwise accumulate and prevent free transmission of fluid therethrough. More specifically stated, the method and apparatus herein disclosed include certain features preventing the formation of excessive carbonaceous obstructions in the course of the vapors, and the danger of such deposits in the highly heated cracking zone and destructive consequences thereof are almost entirely eliminated.

The preferred form of the invention comprises a combination of cooperating elements whereby these and other useful results are effectively accomplished and the advantages of each step preserved while the cracking zone is at a temperature high enough to create an intense cracking reaction followed by free and rapid vaporization. The cracking temperature may be effectively obtained in a highly heated tube or coil discharging into a separating chamber where the vapors are rapidly released and discharged to a reflux condenser. However, if the vapors were discharged at a very high velocity to the reflux condenser, they would carry particles of carbon and high boiling point carbon-forming fractions, and this carbonaceous matter would either accumulate in the vapor passage and form obstructions therein, or pass into the reflux condenser and commingle with the reflux condensate therein, or the carbonaceous matter would be irregularly distributed through the vapor passage and reflux condensate. The period of operation would be thus shortened by ob-

structions in the vapor passage, or by carbonaceous matter passing with the reflux condensate to the highly heated cracking zone where it would tend to obstruct the flow and incur the liability of dangerous overheating, where it lodges against the intensely heated surfaces.

With these conditions in view, the preferred form of the invention includes the separation and removal of carbonaceous matter from the vapors passing from the separating chamber to the reflux condenser. This carbonaceous material is preferably returned to the separating chamber from which it can be readily removed with the residue and discharged from the system, while the clean vapors pass into the reflux condenser to form clean reflux condensate, the latter being returned to the hot cracking zone. Therefore, the cracking operation can be carried on for an indefinite period without incurring the usual danger and expense resulting from carbonaceous obstructions in the vapor line or in the cracking zone.

Another object is to increase the yield of low boiling point fractions, which is most effectively accomplished by a combination of conditions to be hereafter described, though an increase in the yield is promoted by the high temperature and the provision for free evaporation of the residual liquid in the separating chamber. This residual liquid contains carbonaceous matter which is preferably discharged from the system, but it also includes fractions which will evaporate at a high temperature and pass to the reflux condenser for continued refluxing to the cracking zone. High temperature in the separating chamber would therefore increase the yield by evaporation of relatively low boiling point fractions from the residue, and if the temperature is high enough the yield will be further increased by a continued cracking reaction in the separating chamber. I prefer to maintain a cracking temperature in the separating chamber, but it is also desirable to preheat the charging stock by feeding it into the reflux condenser, and if this fresh stock is subjected to a substantial cracking reaction in the reflux condenser, carbon will be formed therein and transmitted to the intake end of the cracking zone where carbon is a source of danger and most undesirable.

- To maintain a cracking condition in the separating chamber and at the same time prevent material cracking of the charging stock in the reflux condenser, I prefer to reduce the temperature of the vapors passing from said chamber to the reflux condenser. This operation also aids in the separation of carbon from the vapors passing to the reflux condenser, as will be hereafter explained.
- 10 The yield can be thus increased by the cracking and free evaporation of fractions which would otherwise be discharged in the residue, and this condition requiring a high cracking temperature in the separating chamber is produced without any material cracking and resultant carbon deposits in the reflux condenser.

- A further object is to increase the yield of the desired low boiling point fractions by retaining in the system substantially all of the high boiling point fractions until they are either converted into the desired product or discharged as residue. This involves the use of a reflux condenser capable of condensing substantially all of the relatively high boiling point fractions, and the reflux condensation should be controlled to prevent the escape of these fractions to the final condenser. Actual experience has shown that to obtain this result, a very large percentage of the vapors should be condensed in the reflux condenser, preferably more than 70 per cent and usually between 80 and 90 per cent. The invention includes a combination of operations particularly adapted for the re-cracking of the reflux condensate and the control of various operating conditions, as will be hereafter explained.

- An important object of the invention is to maintain a predetermined and substantially uniform cracking condition in the cracking zone. It is of course desirable to obtain an intense cracking reaction without causing destructive overheating which would convert many of the gasoline fractions into permanent gas, and my object is to constantly produce the desired reaction, irrespective of variations in other parts of the system. The hydrocarbons passing through the cracking zone preferably include reflux condensate mixed with preheated charging stock, and the reflux condensate may amount to more than 80 per cent of the mixture, this being especially true if the system is effectively controlled to prevent escape of high boiling point fractions to the final condenser, and such control is most advantageous, for it results in a product relatively free from undesirable fractions and causes such fractions to remain in the system until they are either converted into the desired product or discharged as residuum. However, the reflux condensation should be carefully regulated and cannot otherwise proceed with substantial uniformity. Other

conditions in the system are likewise subject to more or less variation during a protracted continuous run, but the greatest danger and the most likely cause for an immediate termination of the entire operation lies in the cracking zone where the hydrocarbons are exposed to a very high temperature. Consequently a substantially uniform condition in this zone is an important factor not only to provide a constant reaction but also to prolong the operation. In the preferred form of the invention, these results are accomplished by pumping the mixture of hydrocarbons at a high velocity through the cracking zone, and by regulating the pump to maintain a substantially uniform rate of flow from the pump to the cracking zone. By establishing and maintaining a substantially uniform high velocity at the pump, the hydrocarbons are rapidly subjected to a uniform reaction, and the unconverted fractions are quickly returned for further cracking.

I will now refer to certain conditions existing in the pump with the understanding that I am the first to actually produce these conditions, and owing to the results derived therefrom, they are regarded as highly important novel features. The reflux condensate is formed at a very high temperature and a saving of time and fuel is gained by returning it to the cracking zone in this hot condition. In the preferred form of the invention, the hot reflux condensate is mixed with preheated charging stock and the mixture is maintained at a high temperature preferably above 600° F., for example, about 750° F. It is desirable to retain in the system a reserve supply of the hot mixture under a pressure of more than 100 pounds per square inch, the most convenient pressure being that of the reflux condenser which may be several hundred pounds per square inch.

While under these conditions of high pressure and high temperature, the mixture is rapidly transmitted to the pump where the pressure is increased to force the hot fluid through the cracking zone to the separating chamber. The increase in pressure at the pump may amount to 100 pounds per square inch, but the degree of additional pressure will depend upon conditions in the cracking zone. Under the particular conditions hereafter given, the hot mixture enters the pump under about 200 pounds pressure, and is discharged under a pressure of about 300 pounds per square inch. Furthermore, the mixture while subjected to these high pressures and temperatures, is very rapidly pumped from the reserve supply to the cracking zone, the rate of flow through the pump being preferably in excess of 90 gallons per minute. In an apparatus of the proportions hereafter described, the hot

mixture can be pumped from the reserve supply to the cracking zone at the rate of 115 gallons per minute, but it is to be understood that the invention is not limited to this 5 rate of flow.

After establishing the predetermined conditions which may, for example, include a reserve supply of reflux condensate and charging stock under a pressure higher than 10 100 pounds per square inch and at a temperature above 600° F., the hot mixture is transmitted to the pump at a rate preferably in excess of 90 gallons per minute, and under these conditions the pump increases 15 the pressure to force the mixture through the cracking zone.

In addition to the advantages of retaining the high temperature and causing a 20 rapid flow and frequent recracking of unconverted fractions, the pump is regulated to maintain a substantially uniform flow which results in a substantially constant and uniform cracking reaction in the cracking zone. The latter feature is quite important, because it provides for a most intense cracking reaction to be maintained indefinitely, without danger of overheating the cracking element.

In using a pump under the conditions 30 heretofore pointed out, it is very important to maintain a substantially uniform rate of flow through the pump, for the temperature in the cracking zone cannot be varied in accordance with irregular variations in the 35 rate of flow, and if the flow is too rapid the desired cracking reaction will not occur. On the other hand, if the rate of flow is too slow, the cracking element under high pressure is subjected to the danger of overheating 40 which is liable to cause a rupture and the danger of fire and explosion. Even a relatively slight overheating may require an immediate stopping of the entire operation, or at least result in destructive conversion of the hydrocarbons into permanent 45 gas.

Therefore, the reserve supply of hot liquid for the pump is a desirable element of the combination. Irregular refluxing, which 50 is bound to occur at some time during a continuous run of many days or weeks, should not be allowed to cause an irregular delivery to the pump. This is true, even though the normal conditions provide for a reserve 55 supply consisting of more than 80 per cent reflux condensate and less than 20 per cent of added charging stock, and I prefer to maintain these proportions in the hot mixture passing through the pump.

60 Another problem involved in maintaining a substantially uniform flow arises when charging stock is added to the extremely hot reflux condensate. The fresh charging stock usually includes low boiling 65 point fractions which will vaporize when

exposed to the high temperature, thereby producing a foam or gas in the liquid passing to the pump. Prior to the present invention, foam produced in this manner has prevented the successful operation of a 70 pump for the purposes herein set forth. In some cases the gas or foam entering the pump has stopped the pumping operation, the foam or gas bubbles having been compressed without leaving the pump cylinder. 75 In other instances, the foam has resulted in a pumping action so irregular that it was necessary to discontinue the operation on account of overheating in the cracking zone.

To overcome this difficulty, the invention 80 includes a preliminary treatment of the fresh charge which actual experience has shown eliminates the danger and disadvantages heretofore incurred by gas or foam due to the presence of boiling liquid in the 85 pump, thereby providing for a substantially uniform rate of flow. Briefly stated, the fresh charge is preheated to vaporize and remove its low boiling point fractions, and the resultant hot liquid substantially free 90 of gas bubbles, or the like, is transmitted with the hot reflux condensate to the pump. In the preferred form of the invention, the desired result is accomplished by preheating the fresh charge in a heat-exchanger 95 forming part of the reflux condenser, and the preheated liquid is then introduced into the vapor space in the reflux condenser.

Unless some precautions are exercised this preheating may cause a rush of unconverted fractions to the final condenser, or it may fail to prevent the consequences resulting from bubbles or foam in the pump, or in the cracking zone. As an illustration of a successful means for accomplishing the desired results, I will hereafter describe a reflux condenser including a heat-exchanger through which the fresh charging stock passes, and a means whereby the preheated stock is divided into a plurality of streams 110 and discharged at different elevations into the vapor space. Retarding elements can be arranged in the vapor space to retard the charging stock falling from one of said elevations to another. If all of the preheated charging stock were admitted into the vapors near the top of the reflux condenser, some of the liquid may be carried away by the vapors passing to the final condenser. On the other hand, if all of the 115 charging stock were admitted near the bottom of the reflux condenser, the charge may not be effectively preheated and the mixture of charging stock and reflux condensate may include the undesirable foam.

I have discovered that by dividing the preheated charging stock into a plurality of streams which enter the vapor space at different elevations, with retarding elements 120 between them, the low boiling point vapors 125

are permitted to freely escape from the charge, without causing an undue rush of vapor or liquid from the top of the reflux condenser, and the hot mixture of reflux condensate and charging stock can be transmitted through the pump without incurring the above mentioned consequences which have heretofore resulted from foam in the pump.

10 Another object is to regulate the temperature in a part of the reflux condenser by varying the flow of charging stock therethrough, at the same time maintaining a substantially uniform delivery of charging stock to the cracking zone.

15 A further object is to control the various factors including temperature in the cracking zone and reflux condenser, the admission of charging stock, the production of reflux condensate and the rate of flow to the cracking zone, in such a manner that a substantially uniform condition is maintained in each part of the system, thereby providing for a continuing operation for very long periods with satisfactory operating conditions throughout the entire system.

20 With the foregoing and other objects in view, the invention comprises the process and apparatus and the novel details hereafter described to illustrate the invention, although it is to be understood that the invention comprehends variations and modifications within the scope of the claims hereunto appended.

25 Fig. 1 is a diagrammatical view of an apparatus embodying the features of this invention.

30 Fig. 2 is a vertical section on a larger scale showing the upper portions of the reflux condenser.

35 Fig. 3 is an enlarged vertical section taken approximately on the line 3—3 in Fig. 1.

40 Fig. 4 is an enlarged detail view showing one of the connecting members for the tubes forming the cracking coil.

45 Fig. 5 is a diagrammatical view similar to Fig. 1 illustrating another form of the invention.

50 Before pointing out the details, I will briefly describe the system shown by Figures 1 to 4 inclusive. A designates a furnace containing a cracking coil B where the cracking reaction occurs, the resultant hot mixture being discharged through an insulated pipe 1 to a separating chamber C. The carbonaceous residue is discharged through one or more of the pipes 2 extending from said chamber to conduct the residue out of the cracking system, as will be hereinafter described. The vapors leaving the separating chamber pass into a reflux condenser D where the high boiling point fractions are condensed while the desired low boiling point fractions pass through a pipe 3 to the final condenser 4.

55 The charging stock enters the vapor space of the reflux condenser through pipes 5 located at different elevations to deliver a plurality of relatively small streams into the vapors. This charging stock is mixed with the reflux condensate and a reserve supply of the mixture is preferably maintained in a reservoir 6 at the bottom of the reflux condenser. A pipe 7 extending from reservoir 6 is provided with branches 8 leading to pumps E and E' respectively, each pump having a discharge pipe 9 leading to the intake pipe 10 of the cracking coil B.

60 The furnace shown by Figs. 1 and 3 comprises a baffle wall 11 located between a burner 12 and the coil B, said wall having ports 13 through which the hot gases pass to the upper portion of the coil. A grid 14 below the coil is provided with ports 15 of varying dimensions for the escape of products of combustion to a flue 16, the smallest ports being near the flue and the largest being remote therefrom, so as to prevent free escape through the ports nearest the flue and cause a substantially uniform distribution of the heat around the cracking coil.

65 The cracking coil may be formed by a number of approximately horizontal tubes 17 as shown by Figs. 1, 3 and 4 and couplings 18, usually termed "return bends" at the ends of the tubes. Removable plugs 19 (Fig. 4) are preferably located in these couplings at points opposite the ends of the respective tubes.

70 The separating chamber C shown in Fig. 1 is an elongated horizontal cylinder covered with heat-retaining insulation 20 and having openings at the top and bottom normally closed by plates or heads 21. A safety valve 22 is mounted on the chamber C. To distribute the hot fluid discharged from the pipe 1 and permit relatively free escape of vapors therefrom, a spreader 23 may be arranged in said chamber as shown in Fig. 1. The spreader shown is in the form of a cone located directly opposite the discharge end of pipe 1 with the apex of the cone facing the pipe.

75 The several pipes 2 for the discharge of residue from the separating chamber are located at different points, so when there is an accumulation of thick carbonaceous matter which cannot freely escape through a pipe at any one of these points, another pipe 120 may be used for the removal of residuum. Each pipe 2 is equipped with a valve as shown in Fig. 1 to control the discharge therethrough, and the intake ends of the pipes may be located at different elevations 125 so the several valves can be operated independently of each other to ascertain the approximate level of the liquid in the separating chamber. The residual matter discharged through pipes 2 passes to a pipe 130

which may lead to a storage tank, the valve 25 being normally closed to prevent return of this matter to the cracking coil.

As an illustration of a suitable reflux condenser in Figures 1 and 2 I have shown a large vertical tower or cylinder 26 above the separating chamber, a heat exchanger including a horizontal drum 27 in direct communication with the cylinder 26 and covered 10 with protective material 28, and an air-cooled drum 29 communicating with said heat exchanger and protected by a shield 30. The protective material 28 may be made of insulation to avoid exposure of the heat 15 exchanger to the varying temperature of the atmosphere, and the shield 30 may be made of metal to perform a similar function and to protect the drum 29 from sudden variations due to rain, snow and the like.

20 To regulate the temperature in the vertical cylinder 26, a jacket 31 surrounding said chamber is provided with one or more doors, or dampers, 32 which may be adjusted to control the admission of air to the bottom 25 of the jacket, the top of said jacket being open at 33 to permit escape of the air.

The air cooled drum 29 at the top of the reflux condenser (Fig. 2) has end walls 34 and air-conducting tubes 35 extending 30 through said walls. The tubes are open for the delivery of air therethrough, and the flow of air may be regulated by adjusting the valves, or dampers, 36 shown in Fig. 2. The outgoing vapors, contacting with the 35 outer faces of the tubes 35, are deflected by baffle plates 37 to flow in the course indicated by an arrow in Fig. 2.

The heat exchanger shown most clearly in Fig. 2, comprises the drum 27 having end 40 walls 38, vertical partitions 39 and a horizontal partition 40. These elements are combined to form an intake compartment 41, a transfer compartment 42 and a discharge compartment 43. A baffle plate 44 is located 45 in the heat exchanger to deflect the vapors as indicated in Fig. 2. 45 designates oil-conducting tubes extending through the partitions 39. In a manner to be more fully 50 explained, the cool fresh charge is pumped through pipe 46 and into the intake compartment 41 from which it escapes through the lower group of tubes 45 below baffle 44 to the transfer compartment 42 and then 55 through the upper group of tubes 45 to the compartment 43 where it is discharged 60 through a pipe 47 equipped with a valve 48 (Fig. 1) to regulate the discharge of surplus charging stock which may be returned to the source of supply (not shown) or otherwise 65 suitably disposed of. However, the pipe 47 is provided with the branches 5 for the delivery of the preheated charging stock to the vapor space, and each branch 5 (Fig. 1) is provided with a valve to regulate the admission of charging stock.

As an illustration of a suitable means for forcing the fresh charge into the cracking system, a pair of pumps F and F' is shown in Fig. 1. The charge supplied through pipe 49 may pass through valve 50 to the intake 70 of pump F, or through valve 50' to the intake of pump F'. The fluid discharged from pump F passes through valve 51 in pipe 52 to the pipe 46, and when the pump F' is in operation the fluid is discharged 75 through pipe 52' and valve 51' to the pipe 46. A by-pass 53 equipped with a pressure-responsive relief valve 54 connects the discharge pipe 52 with the intake of pump F. A similar by-pass 53' provided with a relief 80 valve 54' connects the discharge pipe 52' with the intake of pump F'.

The object in using the two pumps F and F' is to avoid stopping the entire operation 85 when for any reason it becomes necessary to stop the pump. When the pump F is effective, the valves 50 and 51 are open, and the valves 50' and 51' are closed. If it becomes necessary to stop the pump F, the valves 50 and 51 are closed and the companion valves 90 50' and 51' are opened, the pump F' being then used to supply the charging stock. In either case, the active pump may be driven continuously at a substantially uniform speed, and the rate of delivery is regulated 95 by a valve 55 (Fig. 1) in the supply pipe 46. The temperature in the heat exchanger is thus regulated by adjusting the valve 55 to control the flow of charging stock to the 100 heat exchanger. This adjustment will vary the pressure between the valve 55 and the active pump and when this pressure becomes excessive, the pressure-responsive relief valve 54 or 54' is automatically opened to 105 by-pass some or all of the fluid from the outlet to the inlet of the active pump.

The surplus charging stock escaping through pipe 47 is regulated by the valve 48. The admission of charging stock to the vapor space is regulated by the valves in 110 branch pipes 5 through which the preheated charge enters the vapor space of the vertical cylinder 26.

It will now be understood that the delivery 115 of charging stock through the heat exchanger can be regulated by the valve 55 to maintain a predetermined temperature in this part of the reflux condenser. Regardless of the rate of flow through the heat exchanger, the admission of charging stock to the reflux condensate is regulated by the valves in branch pipes 5. Meters 46' and 47' are located near the valves 55 and 48 to indicate the rate of flow through the pipes 46 and 47.

I have heretofore referred to avoiding the presence of gas or foam in the pump E or E', and the importance of releasing the low boiling point vapors from the incoming charge, as a precaution to prevent the foam.

ing. The separate and relatively small streams of preheated charging stock admitted through branch pipes 5 are effectively heated in the vertical cylinder 26 to release 5 the low boiling point vapors before the liquid portion of the charge enters the reservoir 6. If all of the preheated charging stock were admitted at the top of the vertical cylinder 26, the vapors rushing from 10 the reflux condenser would carry with them some of the charging stock. Or, if all of the charging stock were admitted near the bottom of the reflux condenser, the incoming liquid would reach the reservoir 6 without 15 effective removal of the low boiling point fractions, and the boiling liquid in this reservoir would pass to the pump. By admitting relatively small streams of charging stock at different elevations, with baffles 5 20 or other retarding elements between them, the charge is thoroughly preheated without incurring any of the above mentioned disadvantages. The removal of the low boiling point fractions from the incoming 25 charge also reduces the production of fixed gas in the cracking zone.

The mixture of preheated charging stock and hot reflux condensate passes from the reserve supply in reservoir 6 and is conducted through pipes 7 and 8 to either one of the pumps E and E'. When one of these pumps is active, the other is idle, so a reserve pump is always at hand ready for operation when for any reason it becomes necessary or desirable to stop the active pump. Valves 58 control the delivery of the hot mixture through the pump E, and the valves 59 control the delivery through the pump E'. The delivery of steam or other operating medium to the pumps E and E' is controlled to maintain a uniform delivery of the hot hydrocarbon mixture to the cracking coil. In the preferred form of the invention, the pumps E and E' may be operated by steam, and I have shown valves 60 to regulate the delivery of steam to these pumps. A meter 61 in the pipe 10 indicates the rate of flow from the active pump, and this meter is under the observation of the operator in charge of the pumps E and E'.

Near the left side of Fig. 1, 62 designates a pipe equipped with a valve 63 for the admission of steam to the discharge end of the coil. At the end of a run, the valve 64 in discharge pipe 1 may be closed while steam is admitted through pipe 62 and passed backwardly through the coil to clean the same and avoid overheating of carbon-forming liquid therein. At this time, a valve 65 near the intake of the coil may be closed while the steam is discharged through a pipe 66 provided with a valve 67 which is closed during normal operating conditions. The pipe 66 and valve 67 also serve as a means for exhausting the contents of

the cracking coil in the event of a fire resulting from leakage in the coil.

The pressure of the vapors can be regulated in any suitable manner, and preferably by a valve located at any convenient point. For example, a pressure regulating valve 68 (Fig. 1) may be located in the vapor pipe 3 leading from the reflux condenser to the final condenser. A gage 69 is located adjacent to this valve to indicate the vapor pressure, and the valve is preferably regulated to maintain a substantially uniform vapor pressure at the high pressure side of the valve. A thermometer 70 is located in the vapor line adjacent to the valve 68 to indicate the temperature of the vapors passing to the final condenser 4. The temperature of the reflux condenser is preferably regulated to maintain a substantially uniform temperature at the thermometer 70, so that a predetermined and substantially uniform low boiling point product will be obtained from the final condenser.

By grouping together, the thermometer 70, gage 69 control valves 48, 55 and 68, and meters 46' and 47', various elements of the system can be readily controlled by a single operator. 90

The operation may be carried out as follows: 95

At the beginning, when the apparatus is cold and empty and the pressure regulating valve 68 entirely open, the initial charging stock may be admitted through a pipe 71 leading to a pipe 72 connected to the pipes 8. At this time valves 73 and 74 are open and the valve 25 is closed. The incoming charge passes through the selected pump E or E' and rises in the cracking coil. When the coil is filled, the fire in the furnace is started and regulated by a valve 75 at the burner (Fig. 3). The admission of the charge is preferably continued until a substantial body of liquid is supplied to the separating chamber C. Then the admission of fresh charge is discontinued. The valve 76 in the residue line is closed and the valve 73 is also closed, the valves 74 and 25 being open for the direct return of liquid from the separating chamber to the pump E or E'. The operation of this pump is continued to circulate the oil from the separating chamber through the coil and back to said chamber. This circulation results in a preliminary heating while the pressure regulating valve 68 is entirely open, so the air and any water vapor resulting from the heating are expelled through the final condenser. The pressure regulating valve 68 is then completely closed and the circulation through the coil and separating chamber is continued until the desired pressure and temperature are obtained. The oil in the separating chamber is then in a highly heated condition, and normal

operating conditions are established by closing the valves 25 and 74 to prevent flow of liquid from the separating chamber to the pump E or E'. The valve 68 is 5 regulated to maintain a substantially uniform pressure at the gage 69, and the charging stock is continually admitted through the heat exchanger and branch pipes 5. As the carbonaceous residuum accumulates in 10 the separating chamber, it is removed through one or more of the pipes 2 and discharged through pipe 24 and valve 76.

The burner 12 is regulated to maintain a substantially constant temperature in the 15 furnace and the pump E or E' is regulated to maintain a substantially constant flow of hot liquid from the reserve supply in reservoir 6 to the cracking coil. A substantially uniform cracking reaction is thus obtained 20 in the coil, and the desired intense reaction can proceed for an indefinite period without overheating the charge or incurring the danger of rupturing the tubes in the cracking coil.

25 This mixture is therefore in a highly heated condition when it enters the separating chamber, and this insulated chamber may be maintained at a cracking temperature by the heat derived from the cracking 30 coil. The high temperature results in a continuation of the reaction in the hydrocarbons contained in the separating chamber, and a free and rapid evaporation of the relatively low boiling point hydrocarbons in the 35 carbonaceous residue, thereby increasing the yield by preventing undue escape of desirable fractions with the residue. Free evaporation is increased by exposing a large surface of the residual liquid and also by conducting the highly heated vapors in an 40 elongated course over this surface. The vapors released at the intake end of the horizontal separating chamber are permitted to flow at a low velocity to the opposite end 45 where they are discharged to the reflux condenser, and while moving slowly through this course some of the carbon carried in the vapor will drop to the residual liquid.

50 Although important advantages are gained by maintaining the contents of the separating chamber in a very hot condition, this has heretofore resulted in most objectionable carbon deposits in the reflux condenser, and in the prior systems of this kind 55 of which I am aware, the vapors have passed from the separating chamber at a high velocity carrying with them particles of carbon and carbon-forming fractions, as pointed out near the beginning of this specification.

60 Attention is therefore directed to the vertical conduit 77 through which the vapors rise from the separating chamber to enter the reflux condenser, but it is to be understood that this conduit is merely a pre-

fferred means for accomplishing the results to which I will now refer. The conduit is relatively large, and in an apparatus of the proportions to be hereafter given, said conduit may be about 20 inches in diameter and 70 about 12 feet high. The vapors rise in this large conduit at a velocity low enough to permit free precipitation of carbon, and particles of carbon are thus released from the outgoing vapors and dropped into the residue in the separating chamber. Furthermore, the temperature of the slowly rising vapors is preferably reduced to condense the high boiling point carbon-forming fractions, and this preliminary refluxing in conduit 77 causes the return of such fractions to the residue in the separating chamber. Moreover, the condensed high boiling point fractions falling in conduit 77 aid in releasing and knocking down free particles 85 of carbon suspended in the rising vapors.

The cooling of conduit 77 can be conveniently effected by exposing its lower portion to the atmosphere, as shown in Fig. 1, and by maintaining the reserve supply at 6 in 90 contact with the outer face of said conduit, the reserve supply of hot liquid being at a lower temperature than the rising vapors in the conduit.

95 In addition to providing a precipitation conduit for the return of carbonaceous matter, the conduit 77 is preferably utilized to obtain the important advantage of very high temperatures in the separating chamber and at the same time prevent the production of 100 carbon which would result from a corresponding temperature in the reflux condenser. If the charging stock in the reflux condenser were exposed to a temperature approximately the same as the temperature preferably used in the separating chamber, the incoming charge would be subjected to a cracking reaction producing carbon in the reflux condenser. By cooling the vapors passing from the very hot separating chamber, I prevent 105 the disastrous consequences which would be likely to occur if the charge in the reflux condenser were subjected to an intense cracking reaction. I prefer to avoid any substantial degree of cracking in the reflux 110 condenser and thereby materially reduce the danger of adding carbon to the reflux condensate.

115 It will now be understood that the precipitation conduit 77, or its equivalent, performs 120 a number of important functions, each of which very materially increases the efficiency of the system and enables the operation to continue indefinitely without incurring the usual danger and expense which has heretofore resulted from carbon deposits in the system.

125 I will now definitely specify certain operating conditions and proportions of the apparatus which have been entirely satisfac- 130

tory in carrying out the invention, although it is to be understood that the invention is not limited to these particular conditions except as specified in the claims.

- 5 The temperatures at various points may be as follows:

Between about 440° F. and 480° F. in the vapors leaving the reflux condenser, and preferably about 450° F.

- 10 Above 600° F. in the reserve supply of reflux condensate and charging stock in the reservoir 6, and preferably about 765° F. at this point. The reduction in temperature of the fluid passing from reservoir 6 to the intake end of the cracking zone is usually about 15 degrees.

Between about 800° and 900° F. in the stream passing from the cracking coil to the separating chamber, and preferably about

- 20 875° F. The liquid in the separating chamber can thus be maintained at about 845° F. near the intake end of said chamber and about 820° F. near the opposite end. In this event, the vapors will enter the precipitation tube 77 at about 840° F. and over 90 per cent of the hot stream entering the separating chamber will usually pass into said tube in the form of vapor.

- 25 The temperature of the reflux condenser is 30 preferably regulated to condense more than 70 percent of the vapors therein, and to obtain a highly desirable low boiling point product, I usually condense and return to the cracking zone between 80 and 90 percent of the vapors inside of the reflux condenser.

- 35 The admission of charging stock and the reflux condensing action are preferably regulated to produce a mixture in proportions of less than 25 percent charging stock and 40 more than 75 percent reflux condensate. The volume of reflux condensate is preferably 5 to 9 times the volume of added charging stock in the reservoir 6.

- 40 The rate of flow from the pump to the cracking coil is preferably in excess of 90 gallons per minute. In the particular apparatus herein described the mixture of reflux condensate and charging stock at a temperature of 765° in the reservoir 6, can be 45 withdrawn through the pump E or E' and forced to the cracking coil at the rate of 115 gallons per minute, and the pump can be regulated to maintain a substantially uniform rate of flow while the relatively clean 50 mixture, substantially free of carbon and gas or foam, is at a temperature of about 750° F. Assuming that the valve 68 is regulated to maintain a pressure of 200 pounds per square inch at the gage 69, the pressure in 55 the separating chamber and reflux condenser will be about 205 pounds and the hot mixture will enter the pump under a pressure of approximately 205 pounds per square inch. The pressure is greatly increased at the 60 pump to maintain the desired velocity and

cracking reaction in the cracking coil. The increase in pressure at the pump is preferably more than 25 pounds per square inch. In the illustration just given, the hot mixture entering the pump under a pressure of 70 about 205 pounds per square inch is preferably discharged under a pressure of about 300 pounds per square inch. A suitable pump for this purpose is a duplex pump of the reciprocating type operated by steam 75 pressure, and having a stroke of 18 inches, each steam cylinder being 12½ inches in diameter and each oil cylinder being 5½ inches in diameter. The increase in pressure due to the pump may amount to more than 80 100 pounds per square inch, the object being to increase the pressure sufficiently to rapidly force the stream through the cracking zone and obtain a highly effective cracking reaction herein.

85 The dimensions of other parts of an apparatus wherein these various conditions can be obtained and maintained may be as follows:

90 The tubes 17 may be 3½ inches inside diameter, and the 84 of these tubes, each about 23 feet long may be connected to form a suitable coil. The separating chamber can be about 6 feet in diameter and about 40 feet long. The reflux condenser is preferably unusually large in proportion to the other parts, and it is otherwise designed for effective cooling and regulation of the reflux condensation, so as to provide for the proportions of reflux condensate approximately as heretofore pointed out. For example, the vertical cylinder or tower 26 may be about 5 feet in diameter and about 40 feet high, the other elements of the reflux condenser being proportioned approximately as 95 illustrated, with the exception of thicknesses of material and other elements which are 100 enlarged to more plainly appear in the small drawings.

105 The definite disclosure of dimensions, proportions, etc., herein set forth is based upon a system adapted to act upon charging stock such as gas oil or a mixture of gas oil and kerosene distillate at the rate of about 500 barrels per day, so it must be understood 110 that the claims are not in any way limited by this specific description. The invention includes a number of features independent of these proportions, dimensions, etc., even though the novelty of some of the claims 115 may depend upon the proportions herein stated.

120 Fig. 5 illustrates an old apparatus with modifications which adapt it to perform some of the steps in the process herein 125 claimed. In this view, A' designates a furnace provided with a grate 12' for coal, or other fuel, instead of oil, and B' is a coil arranged in the furnace. The hot mixture passing from the coil B' is discharged 130

through pipe 1' into a chamber C', and the object is to completely vaporize the mixture as it enters the chamber C', but since this cannot be entirely accomplished, said chamber 5 is enclosed by a furnace 78 including a grate 79 for a suitable fuel to maintain a relatively high temperature therein.

Carbonaceous residuum may be constantly withdrawn through a discharge pipe 2' extending from chamber C' and provided with a valve 76'. To promote this discharge, steam may be injected through a pipe 80 and valve 81 connected to the pipe 2'. The vapors issuing from the chamber C' enter a vertically elongated precipitation conduit 77' where carbonaceous matter is separated from the rising vapors and dropped into the carbonaceous residue in said chamber. This conduit 77' is cooled by exposure to 10 the atmosphere so as to reduce the temperature of the vapors and condense the fractions having the highest boiling points, substantially as heretofore set forth in referring to the conduit 77. The relatively clean vapors, freed from the precipitated carbonaceous matter, are discharged into a reflux condenser D' including a tower 26' provided with baffles 57', and a jacket 27' surrounding the upper end of said tower. The low 15 boiling point vapors pass through pipes 3^a and 3^b to a final condenser 4'. The pipe 3^a being provided with a valve 68' to regulate the vapor pressure in the system.

A pump 82 is shown in Fig. 5 to force the liquid into and through the coil B' where a high velocity should be maintained, said pump having a discharge pipe 10' connected to the coil. The charge is drawn from a reservoir 6' containing a preheated reserve supply and conducted through an intake pipe 7' to the pump 82. This reservoir 6' is supplied with hot reflux condensate passing from an annular receptacle 6^a at the bottom of the reflux condenser and transmitted 20 through pipe 83 to said reservoir 6'. The charging stock is supplied through pipe 46' to the jacket 27' where it is preheated by the outgoing vapors while serving as a heat exchanger to condense the high boiling point 25 fractions in the vapors. To regulate the temperature of the heat exchanger formed in this manner, the jacket 27' may be provided with overflow pipes 84 at different elevations, each pipe 84 being equipped with a valve to control the flow therethrough. The several pipes 84 are connected to a pipe 30 leading to the reserve supply in reservoir 6'. A further regulation in the temperature of the heat exchanger can be obtained by adjusting a valve 55' through which the fresh charge is supplied to the jacket 27'.

The vapors generated by preheating the charge in jacket 27' escape through a pipe 86 connected to the vapor pipe 3^b.

65 Instead of transmitting the reflux con-

densate from the receptacle 6^a to the reservoir 6', this hot liquid can be conducted to the coil B' by means of pipe 83 and a branch pipe 87. In this event, a valve 88 in said pipe 87 will be open and the valve 89 in pipe 83 will be closed.

In Fig. 5, the lowermost baffle 57' diverts the reflux condensate to the receptacle 6^a to prevent return of this relatively clean liquid through the conduit 77'. In Fig. 1, a similar function is performed by the lowermost baffle 57.

To force the liquid, etc. from the cracking coil B' at the end of a run when the pumping operation is discontinued, a steam supply pipe 90 is connected to pipe 10', said pipe 90 being equipped with a valve 91 to control the admission of steam.

I claim:

1. In the art of cracking hydrocarbons, the process which comprises conducting a stream of hydrocarbons through a cracking zone where a cracking temperature is maintained, discharging the resultant highly heated stream into a separating chamber and 85 depositing the carbonaceous residue in said chamber, maintaining the contents of said separating chamber at a temperature lower than that of said cracking zone but high enough to cause free evaporation of relatively low boiling point liquid in the carbonaceous residue, removing the carbonaceous residue as it accumulates in said separating chamber and discharging it from the system, 90 discharging the vapors in an upward direction from said separating chamber at a velocity low enough to permit free precipitation of carbonaceous matter, at the same time reducing the temperature of the rising vapors to condense high boiling point carbon-forming fractions, continually returning said carbonaceous matter and carbon-forming fractions from the rising vapors to said separating chamber, thereafter condensing the high boiling point fractions in the 95 remaining vapors and thus separating the relatively clean high boiling point condensate from the carbonaceous fractions, mixing additional charging stock with said clean condensate, and continually transmitting the mixture through said cracking zone and into said separating chamber.

2. In the art of cracking hydrocarbons, the process of which comprises conducting a stream of hydrocarbons at a high velocity through a cracking zone where a cracking temperature is maintained, discharging the resultant highly heated stream into a horizontally elongated separating chamber and 120 depositing carbonaceous residue in said chamber, maintaining the contents of said separating chamber at a temperature lower than that of said cracking zone but high enough to permit free evaporation of relatively low boiling point liquid in the car-

- bonaceous residue, spreading the hot liquid as it enters said chamber to permit relatively free escape of the vapors, removing carbonaceous residue as it accumulates in said 5 separating chamber and discharging it from the system, conducting the vapors from said highly heated stream in a horizontally elongated course and at a low velocity over the surface of the liquid in said chamber, then 10 discharging the vapors in an upward direction from said separating chamber at a velocity low enough to permit free precipitation of carbonaceous matter in the rising stream of vapors, continually returning carbonaceous matter from the rising stream to 15 said separating chamber, subjecting the relatively clean vapors to a reflux condensing action to obtain clean reflux condensate, mixing said clean reflux condensate with charging stock, and continually passing the resultant mixture through said cracking zone and into said separating chamber.
3. In the art of cracking hydrocarbons, the process which comprises conducting a 20 stream of hydrocarbons through a cracking zone where a cracking temperature is maintained, discharging the resultant highly heated stream into a separating chamber and depositing the carbonaceous residue in 25 said chamber, maintaining the contents of said separating chamber at a temperature high enough to cause free evaporation of relatively low boiling point liquid in the carbonaceous residue removing the carbonaceous residue as it accumulates in said separating chamber and discharging it from the system, 30 discharging the vapors from said separating chamber in an upward direction and at a velocity low enough to permit free precipitation of carbonaceous material in the rising vapors, at the same time dropping carbonaceous material from the rising stream 35 of vapors to said separating chamber, then subjecting the relatively clean vapors to a reflux condensing action to obtain clean reflux condensate freed from said carbonaceous material, at the same time heating fresh 40 charging stock and removing low boiling point vapors therefrom, mixing the liquid portion of said charging stock with said clean reflux condensate, transmitting the mixture to a pump and thence through said 45 cracking zone and into said separating chamber, and regulating said pump to maintain a substantially uniform cracking condition in said cracking zone.
4. In the art of cracking hydrocarbons, the process which comprises conducting a 50 stream of hydrocarbons through a cracking zone where a cracking temperature is maintained, discharging the resultant highly heated stream into a separating chamber and depositing the carbonaceous residue in said chamber, maintaining the contents of said separating chamber at a temperature high enough to cause free evaporation of relatively 55 low boiling point liquid in the carbonaceous residue, removing the carbonaceous residue as it accumulates in said separating chamber and discharging it from the system, 60 discharging the vapors from said separating 65

chamber in an upward direction and in the form of a vertically elongated rising stream at a velocity low enough to permit free precipitation of carbonaceous material in the rising vapors, at the same time dropping said carbonaceous material from the elongated rising stream of vapors to said separating chamber, then subjecting the relatively clean vapors to a reflux condensing action to obtain clean reflux condensate freed from said carbonaceous material, mixing said clean reflux condensate with additional charging stock, and continually transmitting the mixture through said cracking zone and into said separating chamber. 70

5. In the art of cracking hydrocarbons, the process which comprises conducting a stream of hydrocarbons through a cracking zone where a cracking temperature is maintained, discharging the resultant highly heated stream into a separating chamber and depositing the carbonaceous residue in said chamber, maintaining the contents of said separating chamber at a temperature high enough to cause free evaporation of relatively 80 low boiling point liquid in the carbonaceous residue removing the carbonaceous residue as it accumulates in said separating chamber and discharging it from the system, discharging the vapors from said separating chamber in an upward direction and at a velocity low enough to permit free precipitation of carbonaceous material in the rising vapors, at the same time dropping carbonaceous material from the rising stream 85 of vapors to said separating chamber, then subjecting the relatively clean vapors to a reflux condensing action to obtain clean reflux condensate freed from said carbonaceous material, at the same time heating fresh 90 charging stock and removing low boiling point vapors therefrom, mixing the liquid portion of said charging stock with said clean reflux condensate, transmitting the mixture to a pump and thence through said 95 cracking zone and into said separating chamber, and regulating said pump to maintain a substantially uniform cracking condition in said cracking zone. 100

6. In the art of cracking hydrocarbons, the process which comprises conducting a stream of hydrocarbons through a cracking zone where a cracking temperature is maintained, discharging the resultant highly heated stream into a separating chamber and depositing the carbonaceous residue in said chamber, maintaining the contents of said separating chamber at a temperature high enough to cause free evaporation of relatively 110 low boiling point liquid in the carbonaceous residue removing the carbonaceous residue as it accumulates in said separating chamber and discharging it from the system, discharging the vapors from said separating 115 chamber in an upward direction and at a 120

velocity low enough to permit free precipitation of carbonaceous material in the rising vapors, at the same time dropping carbonaceous material from the rising stream of vapors to said separating chamber, then subjecting the relatively clean vapors to a reflux condensing action to obtain clean reflux condensate freed from said carbonaceous material, at the same time heating 5 fresh charging stock and removing low boiling point vapors therefrom, controlling the reflux condensing action to condense more than 70 percent of the vapors, separately condensing the remaining vapors, 10 controlling the admission of charging stock in accordance with the reflux condensing action to provide a supply of charging stock and reflux condensate in proportions of less than 25 percent charging stock and more 15 than 75 percent reflux condensate, mixing the liquid portion of the charging stock with the hot reflux condensate, pumping the hot mixture through said cracking zone and into said separating chamber, and regulating the 20 pump to maintain a substantially uniform cracking condition in said cracking zone.

7. In the art of cracking hydrocarbons, the process which comprises conducting a stream of hydrocarbons through a cracking zone where a cracking temperature is maintained, discharging the resultant highly heated stream into a separating chamber and depositing the carbonaceous residue in said chamber, maintaining the contents of 30 said separating chamber at a temperature high enough to cause free evaporation of relatively low boiling point liquid in the carbonaceous residue, removing the carbonaceous residue from said separating 35 chamber, discharging the vapors from said separating chamber in an upward direction and at a velocity low enough to permit precipitation of carbonaceous material in the rising vapors, at the same time removing carbonaceous material from the course of the 40 rising vapors, subjecting the relatively clean vapors to a reflux condensing action to obtain clean reflux condensate free of said carbonaceous material, at the same time feeding 45 charging stock into the vapors and mixing said charging stock with the reflux condensate, maintaining a reserve supply of the mixture in a hot condition, continually feeding a stream of the hot mixture from said reserve supply at a uniform rate of flow and 50 forcing the same through said cracking zone and into said separating chamber.

8. In the art of cracking hydrocarbons, the process which comprises conducting a stream 55 of hydrocarbons through a cracking zone where a cracking temperature is maintained, discharging the resultant highly heated stream into a separating chamber and depositing the carbonaceous residue in said chamber, maintaining the contents of said separating

chamber at a temperature high enough to cause free evaporation of relatively low boiling point liquid in the carbonaceous residue, removing the carbonaceous residue as it accumulates in said separating chamber and 70 discharging it from the system, conducting the vapors away from said separating chamber and at the same time removing carbonaceous material from the vapors, subjecting the relatively clean vapors to a reflux 75 condensing action to obtain relatively clean reflux condensate, feeding charging stock into the vapors and mixing said charging stock with the reflux condensate, maintaining a reserve supply of the mixture at a temperature higher than about 700° F., continually feeding a stream of the hot mixture from said reserve supply at a rate of more than about 100 gallons per minute and pumping the same through said cracking zone and 80 into said separating chamber, regulating the pump to maintain a uniform cracking reaction in the cracking zone, and maintaining the cracking zone, separating chamber and said reserve supply under pressures higher 85 than 100 pounds per square inch.

9. In the art of cracking hydrocarbons, the process which comprises subjecting a stream of hydrocarbons to a cracking reaction in a cracking zone, discharging the 95 stream into an insulated separating chamber without greatly reducing the temperature, said chamber being maintained at a cracking temperature by the heat derived from said stream so as to crack some of the 100 constituents of the stream and cause evaporation from the residual liquid in said chamber, conducting the vapors from said chamber at a low velocity through a precipitation conduit rising from said chamber and thereby causing the return by gravity of particles of carbon carried by the vapors, subjecting the relatively clean vapors to a reflux condensing action, mixing charging stock with the clean reflux condensate, forcing the mixture through said cracking zone and into 105 said separating chamber, and removing residuum as it accumulates in said separating chamber.

10. In the art of cracking hydrocarbons, the process which comprises conducting a stream of hydrocarbons through a cracking zone and then into a separating chamber, conducting vapors from said separating chamber to a reflux condenser, continually feeding charging stock through a portion of said reflux condenser to preheat the charging stock and cool the vapors, mixing the charging stock with the reflux condensate, transmitting the mixture through said cracking zone and then into said separating chamber, maintaining the contents of said separating chamber at a temperature high enough to crack said charging stock, and preventing 115 material cracking of the mixture of reflux 120

condensate and charging stock in said reflux condenser by cooling the vapors passing from said separating chamber to said reflux condenser.

- 5 11. In the art of cracking hydrocarbons, the process which comprises conducting a stream of hydrocarbons through a cracking zone and then into a separating chamber, conducting vapors from said separating 10 chamber to a reflux condenser, feeding charging stock into said reflux condenser and mixing it with the reflux condensate therein, maintaining the contents of said separating chamber at a temperature above 800° F., to 15 continue the cracking reaction therein and cause free evaporation of the relatively low boiling point fractions therein, cooling the vapors passing from said separating chamber to said reflux condenser and thereby prevent- 20 ing material cracking of the mixture of reflux condensate and charging stock in said condenser, regulating the reflux condensing action and the admission of charging stock to produce a mixture in proportions of less 25 than 25 per cent charging stock and more than 75 per cent reflux condensate, main- 30 taining a reserve supply of this mixture at a temperature higher than 600° F., continual- 35 ly drawing the hot mixture from the reserve supply and pumping it through said crack- 40 ing zone and into said separating chamber, and regulating the pump to transmit the hot mixture through said pump and into the cracking zone at a predetermined uniform rate of flow greater than 90 gallons per minute.

12. In the art of cracking petroleum hydrocarbons, the continuous process which comprises passing a stream of hydrocarbons 40 through a cracking coil wherein the stream is heated to a temperature higher than 800° F. under a pressure greater than 100 pounds per square inch, discharging the highly heated stream into a separating chamber 45 where the carbonaceous residue is deposited, maintaining the contents of said chamber at a temperature above 775° to continue the cracking reaction therein and at the same time cause free evaporation of relatively 50 low boiling point liquid in the carbonaceous residue, removing residue as it accumulates in said chamber and discharging it from the system, discharging the vapors from said separating chamber in an upward direction 55 and in the form of a vertically elongated stream at a velocity low enough to permit free precipitation of carbonaceous matter in the rising vapors, at the same time cooling the vertically elongated rising stream of 60 vapors to condense its fractions of highest boiling point and knock down particles of carbon from the rising stream to said separating chamber, discharging the remaining 65 vapors into a reflux condenser, supplying charging stock through a portion of the reflux condenser to preheat the charging stock and cool the vapors, permitting escape of vapors from the charging stock, condensing in the reflux condenser more than 75 percent of the vapors from said separating chamber, conducting the remaining vapors to a final condenser, controlling the admission of charging stock in accordance 75 with the reflux condensing action to main- 80 tain in the system reflux condensate and added charging stock in proportions of less than 20 percent charging stock and more than 80 percent reflux condensate, mixing 85 the charging stock with the reflux condensate while in a highly heated condition, main- 90 taining a reserve supply of the hot mixture, continually drawing a stream of the hot mixture from said reserve supply and pumping it through said coil and into said separating chamber, and regulating the pump to obtain a substantially constant pressure 95 and a substantially constant temperature in the mixture discharging from said coil.

13. In the art of cracking petroleum hydrocarbons, the continuous process which comprises passing a stream of hydrocarbons through a cracking coil wherein the stream is heated to a temperature higher than 800° F. under a pressure greater than 100 pounds per square inch, discharging the highly heated stream into a separating chamber where the carbonaceous residue is deposited, maintaining the contents of said chamber at a temperature above 775° to continue the cracking reaction therein and at the same time cause free evaporation of relatively low boiling point liquid in the carbonaceous residue, removing residue as it accumulates in said chamber and discharging it from the system, discharging the vapors from said separating chamber in an upward direction and in the form of a vertically elongated stream at a velocity low enough to permit free precipitation of carbonaceous matter in the rising vapors, at the same time cooling the vertically elongated rising stream of vapors to condense its fractions of highest boiling point and knock down particles of carbon from the rising stream to said separating chamber, discharging the remaining vapors into a reflux condenser, supplying charging stock through a portion of the reflux condenser to preheat the charging stock and cool the vapors, permitting escape of vapors from the charging stock, condensing in the reflux condenser more than 75 percent of the vapors from said separating chamber, conducting the remaining vapors to a final condenser, controlling the admission of charging stock in accordance with the reflux condensing action to maintain in the system reflux condensate and added charging stock in proportions of less than 20 percent charging stock and more than 80 percent reflux condensate, mixing the charging stock with the reflux condensate while in a highly heated condition, maintaining a reserve supply of the hot mixture, continually drawing a stream of the hot mixture from said reserve supply and pumping it through said coil and into said separating chamber, and regulating the pump to obtain a substantially constant pressure and a substantially constant temperature in the mixture discharging from said coil.

13. In the art of cracking petroleum hydrocarbons, the continuous process which comprises passing a stream of hydrocarbons through a cracking coil wherein the stream is heated to a temperature higher than 800° F. under a pressure greater than 100 pounds per square inch, discharging the highly heated stream into a separating chamber where the carbonaceous residue is deposited, maintaining the contents of said chamber at a temperature above 775° to continue the cracking reaction therein and at the same time cause free evaporation of relatively low boiling point liquid in the carbonaceous residue, removing residue as it accumulates in said chamber and discharging it from the system, discharging the vapors from said separating chamber in an upward direction and in the form of a vertically elongated stream at a velocity low enough to permit free precipitation of carbonaceous matter in the rising vapors, at the same time cooling the vertically elongated rising stream of vapors to condense its fractions of highest boiling point and knock down particles of carbon from the rising stream to said separating chamber, discharging the remaining vapors into a reflux condenser, supplying charging stock through a portion of the reflux condenser to preheat the charging stock and cool the vapors, permitting escape of vapors from the charging stock, condensing in the reflux condenser more than 75 percent of the vapors from said separating chamber, conducting the remaining vapors to a final condenser, controlling the admission of charging stock in accordance with the reflux condensing action to maintain in the system reflux condensate and added charging stock in proportions of less than 20 percent charging stock and more than 80 percent reflux condensate, mixing the charging stock with the reflux condensate while in a highly heated condition, maintaining a reserve supply of the hot mixture, continually drawing a stream of the hot mixture from said reserve supply and pumping it through said coil and into said separating chamber, and regulating the pump to obtain a substantially constant pressure and a substantially constant temperature in the mixture discharging from said coil.

the charging stock with the reflux condensate and maintaining a reserve supply of the mixture at a temperature higher than 700° F., continually passing a stream of the hot mixture from the reserve supply and pumping it through said coil and into said separating chamber at a substantially uniform rate in excess of 90 gallons per minute, and regulating the pump to maintain a substantially constant pressure greater than 100 pounds per square inch and a substantially constant temperature above 800° F. in the mixture discharging from said coil.

14. In the art of cracking hydrocarbons, the process which comprises conducting a stream of hydrocarbons through a cracking zone and then into a separating chamber where carbonaceous residue is deposited, conducting the vapors from said separating chamber to a reflux condenser, condensing more than 70 percent of the vapors in said reflux condenser and separately condensing the remaining vapors, at the same time discharging separate streams of charging stock 25 at different elevations into said reflux condenser so as to permit free escape of vapors at said different elevations without causing excessive vaporization at one elevation, mixing the liquid portions of the charging stock 30 with the flux condensate, regulating the admission of charging stock in accordance with the reflux condensing action to obtain a mixture of less than 20 percent charging stock and more than 80 percent reflux condensate, 35 and continually transmitting a stream of the mixture through said cracking zone and into said separating chamber.

15. In the art of cracking hydrocarbons, the process which comprises conducting a stream of hydrocarbons through a cracking zone and then into a separating chamber where carbonaceous residue is deposited, conducting vapors from said separating chamber to a reflux condenser, feeding charging stock 45 through a portion of said reflux condenser while out of contact with the vapors, dividing the preheated charging stock into a plurality of streams, discharging said streams at different elevations into the vapors in said 50 reflux condenser so as to distribute the vapors escaping from said preheated charging stock, regulating the reflux condensing action to condense more than 70 per cent of the vapors passing from said separating chamber, 55 separately condensing the remaining vapors, regulating the admission of charging stock in accordance with the reflux condensing action to obtain a mixture of less than 20 per cent charging stock and more than 80 per cent reflux condensate, causing a reserve 60 supply of the mixture to accumulate and remain in the system, maintaining said reserve supply at a temperature in excess of 600° F., transmitting a stream of the hot mixture at 65 a rate in excess of 90 gallons per minute from

said reserve supply, through a pump and thence through said cracking zone and into said separating chamber, and regulating the pump to maintain a substantially constant rate of flow and a substantially constant pressure and temperature in the mixture passing from said cracking zone to said separating chamber.

16. In the art of cracking hydrocarbons, the continuous process which comprises subjecting a stream of hydrocarbons to a cracking reaction in a cracking zone, discharging the resultant mixture into a separating chamber where carbonaceous residue is deposited, transmitting the vapors from said separating chamber to a reflux condenser, regulating the reflux condensing action to condense more than 70 per cent of the vapors, at the same time admitting charging stock to the reflux condenser and preheating it to a temperature above 600° F., discharging the resultant vapors from the preheated charging stock, controlling the admission of charging stock in accordance with the reflux condensing action to produce a mixture in proportions of less than 25 per cent charging stock and more than 75 per cent reflux condensate, maintaining a reserve supply of said mixture at a temperature in excess of 600° F., constantly pumping the hot mixture from said reserve supply, at a rate in excess of 90 gallons per minute, through said cracking zone and into said separating chamber, subjecting the hot mixture in the pump to a pressure in excess of 200 pounds per square inch, and regulating the pump to maintain a substantially constant and uniform rate of flow in excess of said 90 gallons per minute.

17. In the art of cracking hydrocarbons, the process which comprises the initial steps of supplying charging stock to cracking coil and separating chamber, heating the cracking coil and pumping the charge from said chamber to the coil and back into said chamber, discharging vapor from said chamber, through a reflux condenser and into a final condenser, thereafter confining the vapors to gradually increase the pressure in the system and continuing the pumping operation to and from said separating chamber to gradually increase the temperature of the charge, then proceeding with the normal operations which include preventing escape of liquid from said separating chamber to the pump, conducting a stream of hydrocarbon liquid from a reserve supply and pumping the stream through said cracking coil and into said separating chamber, permitting escape of vapor through said reflux condenser to said final condenser, continually adding reflux condensate and charging stock to said reserve supply and constantly pumping the mixture from said reserve supply, through said cracking coil and into said separating chamber, regulating said pump to maintain

a substantially uniform rate of flow to said coil, and removing carbonaceous residue as it accumulates in said separating chamber.

18. In a cracking apparatus, a cracking tube wherein hydrocarbons are heated to obtain the cracking reaction, a separating chamber wherein carbonaceous residue is deposited, means whereby the hot hydrocarbons are discharged from said cracking tube to said separating chamber, said chamber having an outlet for removal of said residue during the cracking operation, a reflux condenser, a carbon precipitator wherein carbon is released and removed from the course of the vapors, said carbon precipitator comprising a conductor through which vapors pass from said separating chamber to said reflux condenser, and means whereby the reflux condensate, freed from said carbon, is transmitted from said reflux condenser to the intake end of said cracking tube.

19. In a cracking apparatus, a cracking tube wherein hydrocarbons are heated to obtain the cracking reaction, a separating chamber wherein carbonaceous residue is deposited, means whereby the hot hydrocarbons are discharged from said cracking tube to said separating chamber, said chamber having an outlet for removal of said residue during the cracking operation, a reflux condenser, a carbon precipitator wherein carbon is released and removed from the vapors, said carbon precipitator comprising a conductor extending upwardly from said separating chamber to receive the vapors passing from said chamber to said reflux condenser, the area of said conductor being large enough to permit free precipitation of carbon in the vapors rising therein, means whereby charging stock is added to the reflux condensate formed in said reflux condenser, and a pump whereby the mixture of charging stock and reflux condensate is forced through said cracking tube and into said separating chamber.

20. In a cracking apparatus, a cracking tube wherein hydrocarbons are heated to obtain the cracking reaction, a separating chamber wherein carbonaceous residue is deposited, means whereby the hot hydrocarbons are discharged from said cracking tube to said separating chamber, said chamber having an outlet for removal of said residue during the cracking operation, a reflux condenser, a carbon precipitator wherein carbon is released and removed from the vapors, said carbon precipitator comprising a vertical conductor extending upwardly from said separating chamber to receive the vapors passing to said reflux condenser, said vertical conductor being more than 10 inches in diameter and more than 6 feet high to permit release and free precipitation of carbon in the vapors rising therein, and means whereby the reflux condensate formed

in said condenser is transmitted to the intake end of said cracking tube.

21. In a cracking apparatus, a cracking tube wherein hydrocarbons are heated to obtain the cracking reaction, a separating chamber wherein carbonaceous residue is deposited, means whereby the hot hydrocarbons are discharged from said cracking tube to said separating chamber, said chamber having an outlet for removal of said residue during the cracking operation, a reflux condenser, a carbon precipitator wherein carbon is released and removed from the course of the vapors, said carbon precipitator comprising a relatively cool conductor wherein the vapors are transmitted from said chamber to said reflux condenser and at the same time subjected to a preliminary reflux condensation, said relatively cool conductor being in free communication with said separating chamber to permit return of the precipitated carbonaceous matter, and means whereby the reflux condensate, free from said carbonaceous matter, is transmitted from said reflux condenser to the intake end of said cracking tube.

22. In an apparatus for cracking hydrocarbons, a cracking coil wherein the hydrocarbons are heated to obtain the cracking reaction, an elongated horizontal separating chamber wherein a cracking temperature is maintained, said separating chamber having an inlet near one end communicating with said cracking coil to receive the hot hydrocarbons from said coil, the opposite end portion of said chamber being provided with an outlet for the vapors from said hot hydrocarbons so that the vapors released near said inlet are caused to pass through an elongated course to said outlet, said separating chamber having an outlet for the removal of residue during the cracking operation, a reflux condenser, means whereby charging stock is fed through a portion of said reflux condenser, a carbon precipitator through which vapors are conducted from said separating chamber to said reflux condenser to release and remove carbonaceous matter carried by the vapors, said carbon precipitator comprising a vertically elongated relatively cool conduit extending upwardly from said separating chamber to permit free return of precipitated carbonaceous matter and at the same time cool the vapors to prevent material cracking of the charging stock in said reflux condenser, and means whereby the charging stock and reflux condensate, free from said carbonaceous matter, are pumped from said reflux condenser and into said cracking coil.

23. In a cracking apparatus, a cracking tube wherein hydrocarbons are heated to obtain the cracking reaction, a separating chamber wherein carbonaceous residue is deposited, means whereby the hot hydrocar-

bons are discharged from said cracking tube to said separating chamber, said chamber having an outlet for removal of said residue during the cracking operation, a reflux condenser, a carbon precipitator wherein carbon is released and removed from the vapors, said carbon precipitator comprising a relatively cool conductor wherein vapors are transmitted in an upward direction from 5 said separating chamber to said reflux condenser and at the same time subjected to a preliminary reflux condensation, said conductor being in direct communication with said chamber to permit return of precipitated carbonaceous matter, the upper end of 10 said conductor being extended into the lower end of said reflux condenser and spaced from the wall thereof to provide a reservoir of relatively cool reflux condensate around 15 said conductor, means whereby charging stock is fed into said reflux condenser to mix with the reflux condensate, and a pump through which the mixture is drawn from 20 said reservoir and forced through said cracking tube.

24. In a cracking apparatus, means whereby hydrocarbons are cracked and vaporized, a reflux condenser wherein the high boiling point fractions are condensed, a final condenser for the remaining fractions, said reflux condenser including a heat exchanger wherein charging stock is preheated while out of contact with the vapors, the vapor space of said reflux condenser having inlets 30 at different elevations, means whereby separate streams of the preheated charging stock are simultaneously discharged through said inlets, said vapor space being provided with means for retarding the charging stock falling from one of said elevations to another.

25. In a cracking apparatus, a separating chamber wherein carbonaceous residue is deposited, a cracking coil wherein the hydrocarbons are subjected to a cracking reaction and discharged into said separating chamber, a reflux condenser arranged to receive vapors from said separating chamber, said reflux condenser including a heat exchanger wherein charging stock is preheated while 40 out of contact with the vapors, the vapor space of said reflux condenser having inlets at different elevations for the preheated charging stock and said vapor space being provided with means for retarding the charging stock falling from one of said elevations to another so as to permit escape of vapors from the charging stock at different elevations, means whereby separate streams of the charging stock are simultaneously 50 discharged through said inlets and mixed with the reflux condensate at different elevations, and a pump whereby the reflux condensate and the liquid portion of the charging stock are forced through said cracking 55 coil.

26. In a cracking apparatus, means whereby hydrocarbons are cracked and vaporized, a reflux condenser wherein high boiling point fractions are condensed, said reflux condenser including a heat exchanger wherein charging stock is preheated while out of contact with the vapors, regulating means to control the delivery of charging stock through said heat exchanger so as to regulate the vapor temperature therein, a conductor through which preheated charging stock from said heat exchanger is admitted to the vapor space in said reflux condenser, and regulating means to control the flow through said conductor irrespective of rate 75 of flow through said heat exchanger.

27. In a cracking apparatus, means whereby hydrocarbons are cracked and vaporized, a reflux condenser wherein high boiling point fractions are condensed, said reflux condenser including a heat exchanger wherein charging stock is preheated while out of contact with the vapors, regulating means to control the delivery of charging stock through said heat exchanger so as to regulate the vapor temperature therein, a conductor through which preheated charging stock is admitted to the vapor space in said reflux condenser, and regulating means to control the flow through said conductor irrespective of rate of flow through said heat exchanger, said regulating means being adjustable independently of each other, and the outlet of said heat exchanger being provided with a discharge conduit for the surplus 90 charging stock.

28. In a cracking apparatus provided with means for cracking and vaporizing hydrocarbons, a reflux condenser wherein high boiling point fractions are condensed, said reflux condenser including a heat-exchanger wherein charging stock is preheated while out of contact with the vapors, a constantly operating pump whereby the charging stock is forced through said heat-exchanger, temperature regulating means comprising a valve arranged in the course of the charging stock passing from said pump to control the flow through said heat-exchanger, a by-pass for the return of charging stock from the outlet to the inlet of the pump, a pressure-responsive valve arranged in said by-pass to permit said return in response to excessive pressure at the outlet of the pump, separate regulating means to control the delivery of charging stock from said heat-exchanger to the cracking means, and a discharge conduit for the excess charging stock delivered to said heat-exchanger.

29. In the art of cracking hydrocarbons, the process which comprises conducting a stream of hydrocarbons through a cracking zone where a cracking temperature is maintained, discharging the resultant highly 130

heated stream into a separating chamber and depositing carbonaceous residue in said chamber, conducting the vapors from said separating chamber to a reflux condenser, 5 condensing more than 70 per cent of the vapors in said reflux condenser, preheating charging stock to a temperature above 500° F. and removing vapor therefrom, regulating the admission of charging stock in accordance with the reflux condensation to 10 provide a hot reserve supply comprising more than 75 per cent reflux condensate and less than 25 per cent preheated charging stock, transmitting the reflux condensate and charging stock while at a temperature above 500° F. and at a rate in excess of 90 15 gallons per minute through a pump and thence through said cracking zone and into said separating chamber, and regulating the pump to provide a pressure therein exceeding 150 pounds per square inch.

30. In the art of cracking hydrocarbons, the process which comprises conducting a stream of hydrocarbons through a cracking 25 zone where a cracking temperature is maintained, discharging the resultant highly heated stream into a separating chamber and depositing carbonaceous residue in said

chamber, conducting the vapors away from said separating chamber and at the same 30 time removing carbonaceous material from the vapors, subjecting the relatively clean vapors to a reflux condensing action to obtain relatively clean reflux condensate freed from said carbonaceous material, mixing 35 charging stock with said clean reflux condensate and maintaining a reserve supply of the mixture at a temperature above 500° F., regulating the reflux condensation to condense more than 70 per cent of the vapors, 40 regulating the admission of said charging stock in accordance with said reflux condensation so as to provide in said reserve supply a mixture of more than 75 per cent of reflux condensate and less than 25 per cent of added charging stock, constantly pumping a stream of said mixture while at a temperature above 500° F. through said cracking zone and into said separating chamber, and regulating the pump to maintain a substantially constant pressure and a substantially constant temperature in the stream passing from said cracking zone.

In witness whereof, I hereunto subscribe my name to this specification.

FREDERICK B. KOONTZ.
